DESIGN.

R. F. SCHERMERHORN & F. S. WELLER.

HEATING STOVE.

No. 16,346

Patented Oct. 20, 1885.

UNITED STATES PATENT OFFICE.

RODNEY F. SCHERMERHORN AND FERDINAND S. WELLER, OF QUINCY,
ILLINOIS, ASSIGNEES TO WILLIAM V. CHANNON AND JOSEPH W.
EMERY, OF SAME PLACE.

DESIGN FOR A HEATING-STOVE.

SPECIFICATION forming part of Design No. 16,346, dated October 20, 1885.

Application filed July 14, 1885. Serial No. 171,626. Term of patent 7 years.

To all whom it may concern:

Be it known that we, RODNEY F. SCHERMERHORN and FERDINAND S. WELLER, both of the city of Quincy, county of Adams, 5 State of Illinois, have invented a new and original Design for Heating-Stoves; and the said RODNEY F. SCHERMERHORN and FERDINAND S. WELLER hereby declare that the following is a specification of the said new design, reference being had to the accompanying engraving of a heating-stove having said design.

This design embraces several new and distinctive parts which go to make up the whole 15 design, as hereinafter specified.

One integral part of this design is the ornamentation of the side A, which ornamentation consists of the horizontal row of raised circles *a*, having raised rosettes *c* where the circumferences touch.

Another part relates to the ornamentation of the ends of the side A, which ornamentation consists of conventional branches and flowers *d*, displayed alternately with flowers *e*, each decoration marked off from the next by 25 a plain raised bar, *f*.

Another part relates to the ornamentation along the top of the side A, which ornamentation consists of the raised branches and blooms *g*, displayed horizontally and separated 30 by the perpendicular bar of raised scales *h*.

Another part relates to the ornamentation within the space inclosed by the foregoing ornamentation, which consists of seven rosettes, *i*, in a horizontal row across the top of 35 said space, and at either end thereof of a raised upright vine and flowers, *j*, on a rough ground, inclosed by four narrow raised lines in rectangle.

Another part relates to the ornamentation of the side fire-door, B, said fire-door having 40 a flat face with two incut right lines all around near the outside edge thereof, and said ornamentation further consisting of four rows of three mica lights each, *k*, between the inside rows whereof at the top and bottom is a flat surface, and between the center mica-light spaces of the inside rows is a square, *m*, of a size and so displayed that two of its points

touch the outside of said center mica-light spaces, said center square, *m*, having a rough depressed surface, *n*, and a raised rosette, *o*, in each corner thereof.

Another part relates to the ornamentation of the beveled-edged shelf C, which ornamentation consists of decorative perforations *p*, arranged as shown.

Another and further distinctive part of this design is the ornamentation of the top D, which ornamentation consists, across each end of said top D, of the row of raised branches and flowers *q*, alternating with the raised flower *r*, and across the front side of said top D, lengthwise, a straight row of sprays, *s*.

Another part relates to the further ornamentation of the top D, which ornamentation consists of the large vine and flowers E, displayed on a rough surface, terminated above and below by raised lines *t*.

Another part relates to the further ornamentation of the top D, which ornamentation consists of the raised compound ornament F, surrounded by the four raised lines *u*, in rectangle.

Another part relates to the further ornamentation of the top D, which ornamentation consists of the compound ornaments G, displayed on the beveled front corners of the lid-seat H, the bevel flaring upward from a point with a partly concave and partly convex face. 50

The whole design embraces the shape and ornamentation of the side A and top D.

We claim as new—

1. In a design for a stove, the design for the side A, consisting of the parts *a c d e f g h i j*, shaped and ornamented as shown and described.

2. In a design for a stove, the design for the fire-door B, consisting of the parts *k m n o*, shaped and ornamented as shown and described.

3. In a design for a stove, the shape and ornamentation of the shelf C, the same being of the form shown, beveled-edged, and having perforations *p* on the face thereof, all as shown and described.

4. In a design for a stove, the shape and ornamentation of the top D, the same being

(cont)

of the form shown, the ornamentation consisting of the parts *q r s t u F G H*, all as shown and described.

5. The design for the front and top of a heating-stove, embracing the side plate, A, with a side fire-door and shelf, and the top plate, D, all shaped and ornamented substantially as shown and described.

In testimony whereof we hereunto set our hands, in the presence of two subscribing witnesses, this 2d day of July, 1885.

RODNEY F. SCHERMERHORN.
FERNAND S. WELLER.
